(57) **CLAIM**

The ornamental design for a belt clip assembly for a holster, as shown and described.

DESCRIPTION

FIG. 1 is a front perspective view of the belt clip assembly for a holster to be worn inside the waistband of a wearer, illustrated by broken lines in FIG. 8;

FIG. 2 is a front elevational view of FIG. 1;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a pictorial view showing the environment of use thereof.

No claim is made to any of the broken line features on the clip assembly nor to any of the environment of use of the clip assembly.
